(57) CLAIM

The ornamental design for a combined stove and grill, as shown and described.

DESCRIPTION

FIG. 1 is a top, front, and side perspective view of a combined stove and grill showing our new design;

FIG. 2 is a front elevational view thereof;

FIG. 3 is a side elevational view thereof, the side opposite that shown in FIG. 3 being the mirror image thereof;

FIG. 4 is a rear elevational view thereof; and,

FIG. 5 is a top plan view thereof.

The written indicia and propane tank shown in broken lines in the views are for illustrative purposes only and forms no part of the claimed design.
